UNITED STATES PATENT OFFICE

HOLMES B. GRONINGER, OF PORT ROYAL, PENNSYLVANIA

TUYÈRE FOR BLAST FURNACES

Continuation of application Serial No. 366,545, filed May 28, 1929. This application filed October 15, 1929. Serial No. 399,749.

This invention relates to improvements in tuyères particularly serviceable for blast furnaces, and consists in a modification of structure and a consequent adaptation to use which effects economy in manufacture and reduces the frequency of necessary replacements, and so increases the productiveness of the furnace. This application is a continuation of an application filed by me May 28, 10 1929, Serial No. 366,545.

The two figures of the accompanying drawings are fragmentary views in vertical section of the wall of a blast furnace with the tuyère of my invention in place within it. 15 The tuyère is shown with minor differences in detail in the two figures. The blast furnace wall is essentially a wall of masonry 1, into which wall of masonry at proper points are built water-cooled rings 2 (known in

20 the art as coolers) in which the tuyères are placed, and through which the tuyères deliver their intended blasts of air. Tuyères hitherto employed in blast furnaces are tuyères which, when applied, are fixed in their 25 positions within the water-cooled rings. It is a characteristic of the tuyère of my invention that, instead of being fixed and immovable in its position in the water-cooled ring, it is susceptible to advance in axial direction

30 when it is in place in the ring, and it is a further characteristic that the tuyère be such in character that under the wearing-away influence of the furnace heat it still continues to be serviceable. The tuyère, continuing 35 in service through relatively long periods of time, may gradually be consumed as a candle is consumed, and, being fed forward as it is consumed, it may still continue to be serviceable.

40 The tuyère of my invention, as shown in the drawings, is advantageously of cylindrical shape externally. As particularly shown in Fig. I, it consists of a tubular body 4 of refractory material contained within a cylindrical casing 3 of metal. The refractory material chosen will be such as to have the necessary coherence and, subject to inevitable wearing away at its inner end, to endure the 45 conditions of service. Material of suitable refractory nature but lacking coherence may

be employed in the manner shown in Fig. II. The tuyère in this instance consists of a double-walled shell 3, 5, having the space between the walls filled with a body 4. The material which comprises the filling 4 is a 55 highly refractory material,—magnesite, for example, crushed and combined with a suitable binder and rammed to position within the shell; and the material of which the shell is formed is such as to give support to the 60 body of rammed-in refractory, and to afford rigidity to the whole, adapting the article to conditions of handling, and to enable it to be fed axially through the cooling ring. Advantageously this double-walled shell may be 65 formed of cast steel, and in the form shown in Fig. I, the casing 3 may be formed of cast steel.

A wedge-ring 30, having an inwardly tapering surface to abut the similarly tapered 70 surface 20 of the cooling ring, has an inner cylindrical surface 10 by which the tuyère is desirably supported. In furnace operation the exposed end of the tuyère with- 75 in the furnace often becomes coated with slag, or covered by a scum of metal which would prevent ready removal of the tuyère from the cooler, were it not for the wedge-ring. Obviously, the cooling ring 2 could be 80 formed to provide a tuyère-supporting surface, but advantageously this surface is provided within a wedge-ring which may unseat to give ample clearance as the worn-out tuyère is withdrawn from the cooling ring. The drawings show the tuyère in place 85 in the ring. It projects, as the tuyère of standard construction projects, through the ring in the furnace wall and into the furnace chamber. The inner end of the tuyère, the right-hand end, is exposed to the intense 90 heat developed within the furnace as operation progresses, and, accordingly, the inward projecting end of the tuyère wastes away with relatively great rapidity. As the tuyère of my invention so wastes away, it is from 95 time to time fed axially forward in direction from left to right, as seen in the drawing, and so maintained serviceable while its length diminishes. By way of explanation, though not by way of limitation, the tuyère 100

when newly applied may be three feet long, more or less; and, when it is in place, it may project beyond the furnace wall and into the furnace chamber as much as nine to twelve ⁵ inches.

I have spoken of the withdrawal of the tuyère from right to left through the cooler. Although in the course of the serviceable life of a tuyère there may be occasion so to withdraw it, when it has so far wasted away that its usefulness is ended, a preferable procedure may be to drive the stub of the tuyère forward and let it be lost in the furnace charge, and to replace it with a fresh tuyère introduced behind it.

In Fig. I, I have shown the wedge-ring ³⁰ as a solid body; but manifestly, it too may be a hollow and water-cooled body, in that respect of like construction with the cooler in

²⁰ which it rests, and it is so shown in Fig. II. The tuyère is the nozzle of the blast pipe, and it will be understood that the connections through which the blast of air is brought and delivered through the tuyère are ²⁵ adapted to admit of such progressive advance of the tuyère in axial direction, to compensate for the wearing away to which it is subjected. Such adaptation of the blast connections may manifestly be made in convenient manner.

I may form the shell ⁵ of the tuyère of Fig. II with a helical indentation ⁶ impressed upon it. Obviously, the so rifled inner cylindrical wall of the tuyère will be effective to give a swirl to the blast of air as it enters the furnace. Such indentation, furthermore, will be an aid in retaining the essential refractory body ³⁵ 4 between the two cylindrical walls.

⁴⁰ It is preferred, in forming the tuyère of Fig. II to form the double-walled shell closed at one end, as at ⁷, and open at the opposite end (the end which becomes the inner end in service), as the drawing shows, and ⁴⁵ through this open end to introduce and ram the filling ⁴ of refractory material. It could be a matter of no importance if the shell at the inner (right hand) end were closed and the opposite end left open for filling, for in ⁵⁰ service the closing web would in a very short time be consumed. Essentially, my tuyère is an annulus or tube of refractory material suitably carried in a metallic case.

⁵⁵ I claim as my invention:

1. A tuyère for a blast furnace including a support with a cylindrical opening adapted to be set in the furnace wall with its said opening extending through the wall, a cylindrical tube of refractory material arranged ⁶⁰ in the opening in the said support and progressively adjustable in an axial direction in such opening.

2. In a blast furnace structure and in combination with a cooling ring, a tuyère consisting of an annulus of refractory material

adapted to be advanced axially in its position in the ring as under conditions of furnace operation it is at its inner end worn away.

3. In a blast furnace installation the combination of a cooling ring and a tuyère consisting of a body of refractory material of cylindrical form exteriorly, adjustable longitudinally within said ring. ⁷⁰

4. In a blast furnace installation the combination of a cooling ring provided with an internal cylindrical bearing surface and a tuyère provided with an exterior cylindrical surface adjustably borne by said cooling ring upon its said internal cylindrical surface. ⁷⁵

5. In a blast furnace installation the combination of a cooling ring provided with a wedge-ring having an internal cylindrical bearing surface, and a tuyère provided with an exterior cylindrical surface adjustably borne by said wedge-ring upon its internal cylindrical surface. ⁸⁰

In testimony whereof I have hereunto set my hand.
